UNITED STATES PATENT OFFICE.

JOHN N. SELVIG, OF CHICAGO, ILLINOIS.

METHOD OF AND APPARATUS FOR TREATING FIBROUS MATERIAL.

Application filed March 10, 1927. Serial No. 174,116.

My invention relates to methods of and apparatus for treating fibrous material and has for its object the provision of a new and improved method of preparing the fibers of 5 hemp, sisal grass, flax, or similar products for use. It is another object of my invention to provide one form of new and improved apparatus by the use of which my improved method can be carried out.

10 It is one of my objects to provide a new and improved form and arrangement of parts in a machine for preparing fibers involving more or less the structures described and claimed by my Letters Patent No. 15 1,601,984, granted on October 5, 1926. To this end, it is one of my objects to provide a construction comprising breaking and scutching means of the type set forth in said Letters Patent, together with improved 20 means for holding the fibers and controlling their movement through the machine while being acted upon. It is another object of my invention to provide a new arrangement by which the hemp, flax, or other material, is fed in a diagonal direction to the breaking and scutching apparatus whereby the capacity 25 of the machine is very materially increased as compared with the construction in which the material is fed between the beaters of the scutching and breaking apparatus at right angles with respect to their axes of rotation. It is one of the objects of my invention to provide a plurality of beater 30 devices to which the fibers are fed successively, with one of the devices acting on the middle portions of the fibers in one direction and the other device acting on said middle portions in the opposite direction as the diagonal feeding proceeds.

35 40 It is another object of my invention to improve methods and apparatus of this type in sundry details hereinafter pointed out. The preferred means by which I have accomplished my several objects are illustrated in 45 the accompanying drawings and are herein-after specifically described. That which I believe to be new and desire to cover by this application is set forth in the claims.

In the drawings,—

50 Fig. 1 is a top plan view of the preferred form of my improved machine.

Fig. 2 is a side view of said machine, omitting however the portion thereof below the floor upon which the main frame of the machine is located.

55 Fig. 3 is an enlarged detail, partly broken

away, being substantially a vertical cross section on line 3—3 of Fig. 1.

Fig. 4 is an enlarged detail, being substantially a vertical section taken on line 4—4 of 60 Fig. 11.

Fig. 5 is a fragmentary side view of one of the forwarding chains in position upon the table of the machine.

Fig. 6 is an enlarged detail, being a vertical 65 section taken at the line 6—6 of Fig. 11.

Fig. 7 is an enlarged detail, being substantially a vertical section taken at line 7—7 of Fig. 4.

Fig. 8 is a vertical section through a pair 70 of scutching reel devices, being substantially a section taken at line 8—8 of Fig. 1.

Fig. 9 is an end view of a pair of breaking and scutching reels, being taken substantially on the section line 9—9 of Fig. 1.

Fig. 10 is a vertical section taken on line 75 10—10 of Fig. 9.

Fig. 11 is a top plan view of the receiving end portion of my improved machine, being shown upon an enlarged scale for better 80 illustrating the construction, and showing the end portion of the reel in longitudinal section.

Fig. 12 is an enlarged detail view, being a 85 section at line 12—12 of Fig. 13; and

Fig. 13 is a top plan view of the middle portion of my improved machine upon an enlarged scale and showing certain of the parts in section.

Referring to the several figures of the 90 drawings, in which corresponding parts are indicated by the same reference characters, 20 indicates a table supported by a framework 21 of any suitable type. As is best shown in Fig. 8, the table 20 comprises a portion of a housing 22 by which the operating parts of my improved machine are substantially enclosed, the housing in some instances forming also a part of the framework. In the form of my improved machine as shown 100 in the drawings, four sets of scutching reels are provided arranged at opposite sides of the table 20, as is best indicated in Fig. 1, each pair of scutching reels being preferably of substantially the form illustrated and 105 claimed in my prior Patent No. 1,601,984 above referred to. Each pair of reels comprises two shafts 23 and 24 in spaced relation to each other, said shafts in the construction shown being provided at their end portions 110 with spiders 25, the arms of one of the spiders being in staggered position with respect

to the arms of the other spider, to which they are connected by diagonally disposed longitudinally extending scutching bars 26. It will be understood that additional spiders 5 might be provided if desired. The scutching reels located nearer to the receiving end of the machine act not only as scutching reels but also as breaking devices, the operation of the reels being substantially as described 10 in my aforesaid Letters Patent.

The housing below each pair of reels terminates at the bottom in a hopper 27 which has a pipe 28 leading downwardly therefrom through the floor. The several pipes 28 from 15 the four sets of scutching reels are connected with a suction pump 29 of any suitable type driven by power from any available source, the arrangement being such that the pump serves to draw from the machine the broken 20 pieces of the stalks and the dirt and dust arising from the breaking and scutching operations.

The upper shaft 23 of each of the pairs of scutching reels is provided at one end with 25 a driving pulley 30 which is adapted to be driven by power from any suitable source. The shafts 23 and 24 are connected by gears 31 and 32 for causing them to rotate in opposite directions (see Fig. 11) the reels being 30 positioned so as to operate in interlapping relationship as is clearly shown in Figs. 8 and 9. In the end portion of the table 20 at the left in Fig. 1, I have provided a slot 33 (see Fig. 6) through which the upper ends 35 of lugs 34 extend, such lugs being formed upon the outer face of an endless chain 35 supported by sprocket gears 36 and 37 mounted on shafts 38 extending transversely across the table 20 a short distance below its 40 bottom face. At opposite sides of the chain 35, but located above the table rather than below, I have provided two additional chains 39 and 40. Each of the chains 39 and 40 is supported at its rear end by a sprocket gear 41 mounted upon a transverse shaft 42. The front end of the chain 39 is supported by a 45 sprocket gear 43 revolubly mounted in position, while the front end of the chain 40 is supported by a sprocket gear 44 considerably 50 farther in advance than the gear 43. The chains 39 and 40 pass over sprocket gears 45 mounted upon a drive shaft 46 extending transversely of the table whereby the chains are actuated for carrying the bottom plies 55 of the chains forwardly, or toward the right in Fig. 3. Idler gears 47 are employed in connection with the chains 39 and 40 for tightening the chains by the adjustment of the gears 47 vertically by means of swinging 60 arms 48 upon which such gears are mounted. The chain 35 is also driven from the shaft 46 by means of a gear 49 mounted on the shaft 46, the gear 49 meshing with a gear 50 (see Fig. 2) which is connected by means of a 65 sprocket chain 51 and suitable sprocket gears

with the shaft 38 upon which the sprocket gear 37 for the chain 35 is mounted. The arrangement is such that the side chains 39 and 40 are driven at a slightly greater speed than the chain 35. The shaft 46 is driven by 70 power applied thereto through a driving pulley 52. As is clearly shown in Fig. 5, the chain 39 is provided with a series of outwardly projecting lugs 53 which extend into contact with the table 20 or into close proximity 75 thereto, the chain 40 being similarly formed and similarly positioned.

At the forward end of the machine, I have provided a drive shaft 54 with a driving pulley 55 thereon for applying power thereto 80 from any suitable source. A sprocket chain 56 by means of suitable sprocket gears connects the shaft 54 with a drive shaft 57 at about the middle point of my machine. The shaft 57 is provided with a sprocket gear 58 which is connected by means of an endless chain 59 with a sprocket gear 60 substantially opposite the forward end of the bottom chain 35. As is best shown in Fig. 7, the sprocket gear 60 in the construction shown 85 comprises two parts for accommodating the particular form of chain 59 as hereinafter described, such two parts being rigidly mounted in any suitable manner upon a hub 61 which is rotatably supported from the framework by the use of any suitable mechanism. As is shown in Figs. 4, 7 and 11, the chain 59 comprises three series of longitudinally extending rib sections, each series being spaced transversely with respect to the other series, and the rib sections of the intermediate series being wider than the ribs of the other two series. That is to say, the chain 59 is a sprocket chain with the connecting plate 90 portions of the chain forming in effect substantially continuous ribs longitudinally of the chain. In the drawings the wider intermediate rib portion is indicated by the numeral 62, while the outside rib portions are indicated by the numerals 63. As is best 95 shown in Fig. 4, the outer edges of the ribs 62 and 63 are provided with teeth therealong. On the ends of the hub 61, there are two toothed feed wheels 64 and 65 in such spaced 100 relation as to permit the chain 59 to have free movement between them, the teeth of such feed wheels being spaced a small distance from the top face of the table 20, as is clearly 105 shown in Fig. 4.

Upon the table 20 below the chain 59, I 110 have provided longitudinally extending ribs 66 and 67 having their smooth upper edges substantially opposite the lower edges of the rib portions 63 of the chain, with the rib portion 62 extending downwardly between the ribs 66 and 67, the rear ends of the ribs 66 and 67 being beveled so as to permit the stalks of fibrous material readily to be pushed 115 upwardly thereon as hereinafter described.

In front of the chain 59, with its rear 120

end for a short distance opposite the front end of said chain 59, I have provided a second main chain, indicated by the numeral 68. This chain is very similar to the chain 59, except that in the form shown it comprises four longitudinally extending rib portions 69 in place of the three similar portions of the chain 59. The rib sections 69 of the chain 68 are, however, all of the same width 10 vertically, so that their outer edges which are provided with teeth therealong all stand opposite each other. In place of the two ribs 66 and 67 used in connection with the chain 59, I provide five stationary longitudinally extending ribs 70 on the top face 15 of the table 20 below the chain 68, the smooth top edges of the ribs 70 extending upwardly into the spaces between the ribs 69 of the chain.

20 The rear end of the chain 68 is supported by a sprocket gear 71 revolvably mounted on the frame-work 21, such sprocket gear being of the same type as the gear 60 but arranged to accommodate the greater number of longitudinally extending rib portions 70. At 25 its front end, the chain 68 is supported by a sprocket wheel 72 by which it is also driven, such gear 72 in turn being driven from the shaft 54 by a chain 73 and sprocket gears 30 cooperating therewith, as is best indicated in Fig. 1.

With power applied to the several pulleys 30, to the pulley 52, and the pulley 55, and with the suction pump 29 in operation, stalks 35 of fibrous material are placed in position across the rear end of the table 20 and are pushed forward along the table until they come into position to be drawn forward by the side chains 39 and 40 and the bottom 40 chain 35. As will be readily understood, since the side chains are driven at a slightly faster rate than that of the bottom chain, the stalks will be buckled or bent at their middle portions so that each end portion of the stalk 45 extends diagonally forward to a slight extent, the degree of angularity of the end portions increasing as the stalks move forward. Very soon, however, the stalks are moved out of engagement with the bottom chain 35, 50 at about the same time coming into engagement with the feed wheels 64 and 65 which force the stalks up the beveled ends of the ribs 66 and 67 into engagement with the main chain 59. In Fig. 7, I have shown two stalks 55 74 and 75, one just ready to pass up the beveled ends of the ribs 66 and 67, and the other crimped between the ribs of the chain 59 and the smooth upper edges of the ribs 66 and 67. With the stalk 75 in the position 60 as shown, it will be understood that it will resist a fairly strong pull longitudinally of the stalk and transversely of the table without any substantial slippage longitudinally of the stalk.

65 As the stalks of fibrous material are car-

ried forward by the side chains 39 and 40 and the main chain 59, the ends of the stalks are brought successively into engagement with the breaking and scutching mechanism at the left in Fig. 1. In the construction 70 illustrated, the side chains 39 and 40 and the main chain 59 are driven at the same speed so that the stalks are normally held in the same bowed angular position as that which they have when they pass into engagement with the main chain. Inasmuch as the axes of the breaking and scutching reels are diagonally disposed with respect to the forward movement of the stalks along the table 20, it will be understood that the 80 stalks of fibrous material will be presented gradually farther and farther into effective engagement with the reels for the breakage of the woody matter into short pieces and the scutching of such woody material from 85 the fibers. The action of the breaking and scutching reels is substantially the same as that set forth and claimed in my prior U. S. Patent No. 1,601,984 above referred to, comprising the bending of the stalks first in one 90 direction and then at substantially the same point in the opposite direction for securing the complete breakage of the woody matter for facilitating its removal by the scraping or scutching action of the longitudinally 95 extending bars of the reels as the stalks move forward under the influence of the chains as above described. By the action of the breaking and scutching reels at the left in Fig. 1, which reels converge forwardly with 100 respect to the path of movement of the stalks, a scutching operation is effected progressing from the ends of the stalks toward the intermediate portions thereof at which they are held by the main chain 59.

105 As the stalks progress to and beyond the forward end of the first set of breaking and scutching reels, the opposite ends of the stalks are brought into effective engagement with the breaking and scutching reels at the opposite side of the table 20, such reels also converging forwardly with respect to the path of movement of the stalks. By such reels, the stalks at that side of the table are broken in the manner above described and a scutching 110 operation is effected progressing from the ends of the stalks at that side of the table toward the intermediate portions at which the stalks are held by the chain 59. While the stalks are still in engagement with the 115 last mentioned breaking and scutching reels, they pass out of the control of the main chain 59 and into the control of the second main chain 68. Inasmuch as the major portions of the woody matter have been scutched from the stalks so as to leave substantially nothing but the fibers by the time they are brought into engagement with the second main chain 68, I have provided the slightly different 120 form of main chain 68 as illustrated in Fig. 130

12. In said Fig. 12 I have indicated the fibers in engagement with the main chain 68 by the numeral 76. By reason of the considerable number of the longitudinally extending ribs 69 and of the longitudinally extending ribs 70 in interlapping relationship with such ribs 69, the main chain 68 is rendered effective for holding the fibers against movement longitudinally of the fibers transversely of the table even though such fibers are comparatively fine and soft.

At opposite sides of the table 20, to the right of the breaking and scutching reels just referred to as shown in Fig. 1, I have provided additional breaking and scutching reels of the same type and having substantially the same effect, except that the second set of reels at each side diverge forwardly with respect to the movement of the stalks or fibers so that the scutching operation of such reels progresses in each instance from an intermediate point toward the ends. It will be understood that when the stalks pass out of engagement with the main chain 59 and into engagement with the main chain 68, the breaking and scutching operation is carried to and beyond the point where such stalks were originally in engagement with the chain 59, so that the stalks are completely scutched from end to end by the several operations as above described.

For conducting the fibers from the first set of breaking and scutching reels at the side of the table 20 and into operative engagement with the next succeeding set of reels at the same side of the table, guides 77 and 78 are provided. As is best shown in Figs. 9 and 10, the guide 77 is of substantially a conical shape for conducting the fibers in their forward movement along the table to the proper point for entering into engagement with the second set of reels at that side of the table. As is clearly shown in Fig. 10, the forward ends of the longitudinally extending beater bars 26 of the lower reel at the left in Fig. 1 are notched at 26^a on their inner faces for the reception of the rear end of the guide 77 so that the fibers may pass smoothly without interruption from the lower reel to the guide 77. I have not shown in detail the form of the guide 78, but it will be understood that it is of corresponding shape and operation.

By the use of my improved mechanism, the initial breaking and scutching of the fibers by the first acting sets of reels at each side of the table are very effective for clearing the greater part if not all of the woody matter from the fibers. In the treatment of some types of fibrous material in proper condition for the treatment, the fibers will be found to be properly cleaned by the action of such first acting sets at opposite sides. For flax, however, and some other kinds of fibrous material, I prefer to employ one or more sets

of scutching mechanisms in addition to said first acting sets, such additional scutching mechanisms as above described serving to carry the scutching operations in the opposite direction at each end portion from that of the initial scutching operation. By this means, the fibers are very thoroughly cleaned, while at the same time they are kept in the best possible condition without tangling or breakage.

75 I have found in practice in the use of my improved machine that it is very effective in its operation, serving to clean the fibrous material even when the stalks are run through the machine at a comparatively very rapid rate.

80 While I prefer to employ the form of machine substantially as shown in the drawings and as above described, I do not wish to limit my invention thereto, except as certain of the claims are specifically so limited, since it will be evident that changes might well be made in the form and construction without departing from the spirit of my invention.

85 I claim:—

90 1. The method of scutching fibrous material which comprises feeding the material successively to two sets of rotary beaters arranged in diagonal position with respect to the path of movement, with one set diverging forwardly with respect to said path and the other set converging.

95 2. An apparatus for treating fibrous material, comprising in combination a table, means for feeding stalks of fibrous material forward along said table, other feeding means at opposite sides for feeding the end portions of the stalks forward at a slightly faster rate serving to give the stalks a slight bend at their middle portions, other means to which said first named feeding means delivers said stalks for feeding them forward evenly in bent condition, and two reels having longitudinally extending beater bars revolving in interlapping relationship at the 100 edge of the table with their axes diagonally disposed with respect to the direction of movement of the stalks.

105 3. An apparatus for treating fibrous material, comprising in combination a table, an endless belt for feeding stalks of fibrous material forward along said table, other endless belts at opposite sides for feeding the end portions of the stalks forward at a slightly faster rate serving to give the stalks 110 a slight bend at their middle portions, a fourth endless belt to which said first named belt delivers said stalks for feeding them forward evenly with the side belts, and two reels having longitudinally extending beater 115 bars revolving in interlapping relationship at the edge of the table with their axes diagonally disposed with respect to the direction of movement of the stalks.

120 4. An apparatus for treating fibrous ma-

- terial, comprising in combination a table having a slot therein, an endless chain having upward projections extending through said slot adapted by engagement with stalks 5 of fibrous material to feed them forward along said table, other endless chains at opposite sides for feeding the end portions of the stalks forward at a slightly faster rate serving to give the stalks a slight bend at 10 their middle portions, a fourth endless belt to which said first named endless belt delivers said stalks for feeding them forward evenly with the side chains, and two reels having longitudinally extending beater bars 15 revolving in interlapping relationship at the edge of the table with their axes diagonally disposed with respect to the direction of movement of the stalks.
5. An apparatus for treating fibrous material, comprising in combination a table having a slot therein, an endless chain having upward projections extending through said slot adapted by engagement with stalks of fibrous material to feed them forward along 20 said table, a pair of ribs extending longitudinally of the table from one end of said chain and in alignment therewith, a second endless chain mounted above said ribs and having thereon a longitudinally extending 25 toothed rib projecting downwardly between said first named ribs serving to crimp stalks of fibrous material between the first named ribs and to draw said stalks along the upper edges of the first named ribs, and other endless 30 chains mounted on said table at opposite sides of said first and second chains in position to press the end portions of the stalks against the table and having downward projections thereon serving by contact 35 with the stalks to carry said end portions forward at the same speed as that of the portion gripped by the ribs, said first named endless chain being driven at a slower speed than said second chain whereby the stalks 40 when in engagement with said first chain are gradually bent forwardly at their end portions.
6. An apparatus for treating fibrous material, comprising in combination a table having a slot therein, an endless chain having upward projections extending through said slot adapted by engagement with stalks of fibrous material to feed them forward along said table, a pair of ribs extending 45 longitudinally of the table from one end of said chain and in alignment therewith, a second endless chain mounted above said ribs and having thereon a longitudinally extending toothed rib projecting downwardly 50 between said first named ribs serving to crimp stalks of fibrous material between the first named ribs and to draw said stalks along the upper edges of the first named ribs, a toothed feed wheel above the end of 55 said second endless chain adapted to assist 60 in carrying the stalks of fibrous material from said first named chain into the grip of said ribs, and other endless chains mounted on said table at opposite sides of said first and second chains in position to 65 press the end portions of the stalks against the table and having downward projections thereon serving to carry said end portions forward, said second endless chain and said last named endless chains being arranged 70 to run at the same speed and said first named endless chain being arranged to run at a slightly slower speed whereby the stalks are 75 bent forwardly at their end portions.
7. An apparatus for treating fibrous material comprising in combination a table, means for feeding stalks of fibrous material forward along said table, two reels having longitudinally extending beater bars revolving in interlapping relationship at the edge 80 of the table with their axes converging with the path of movement of the stalks for receiving the stalks gradually between the reels as they move forward along the table, two other reels having longitudinally extending 85 beater bars revolving in interlapping relationship at the edge of the table in front of said first named two reels with their axes diverging from the path of movement of the stalks for scutching the fibers as they pass 90 gradually out of engagement with the reels in their forward movement, and a guide extending from the first pair of reels to the second pair for directing the fibers into engagement with the second pair of reels. 95
8. An apparatus for treating fibrous material comprising in combination a table, means for feeding stalks of fibrous material forward along said table, two reels having longitudinally extending beater bars revolving in interlapping relationship at the edge 100 of the table with their axes converging with the path of movement of the stalks for receiving the stalks gradually between the reels as they move forward along the table, two other reels having longitudinally extending 105 beater bars revolving in interlapping relationship at the edge of the table in front of said first named two reels with their axes diverging from the path of movement of the stalks for scutching the fibers as they pass 110 gradually out of engagement with the reels in their forward movement, and a guide underlying the longitudinal bars of the lower reel of the first pair and extending to said 115 second pair of reels for delivering the fibers thereto as they are moved forward along the table. 120
9. An apparatus for treating fibrous material comprising in combination a table, means for feeding stalks of fibrous material forward along said table, two reels having longitudinally extending beater bars revolving in interlapping relationship at the edge 125 of the table with their axes converging with 130

- the path of movement of the stalks for receiving the stalks gradually between the reels as they move forward along the table, two other reels having longitudinally extending beater bars revolving in interlapping relationship at the edge of the table in front of said first named two reels with their axes diverging from the path of movement of the stalks for scutching the fibers as they pass gradually out of engagement with the reels in their forward movement, and a conical guide interposed between the two sets of reels for delivering the fibers from the first set to the second, the longitudinally extending bars of the lower reel of the first pair being notched for receiving the larger end of said guide.
10. An apparatus for treating fibrous material, comprising in combination means for gripping stalks of fibrous material and moving them forward, breaking and scutching means at one side of the path of movement operating on said stalks progressively from one end toward the middle, other breaking and scutching means at the opposite side operating on said stalks progressively from the other end toward the middle, additional scutching means operating progressively on said stalks toward the end of the stalks at one side, and other additional scutching means at the opposite side operating progressively on said stalks toward the end of the stalks at that side.
11. An apparatus for treating fibrous material, comprising in combination means for gripping stalks of fibrous material and moving them forward, two reels having longitudinally extending beater bars in interlapping relationship arranged in diagonal position with respect to the path of the stalks for operating on said stalks progressively from one end toward the middle, a second set of two reels having longitudinally extending beater bars in interlapping relationship arranged in diagonal position with respect to the path of the stalks at the opposite side thereof for operating on said stalks progressively from the other end of the stalks toward the middle, and a third set of two reels having longitudinally extending beater bars in interlapping relationship arranged in diagonal position with respect to the path of the stalks at the same side thereof with said first named reels operating progressively on the intermediate portions of said stalks.
12. An apparatus for treating fibrous material, comprising in combination means for gripping stalks of fibrous material and moving them forward, two reels having longitudinally extending beater bars in interlapping relationship arranged in diagonal position with respect to the path of the stalks for operating on said stalks progressively from one end toward the middle, two other reels also having longitudinally extending beater bars in interlapping relationship arranged in diagonal position with respect to the path of the stalks at the opposite side thereof for operating on said stalks progressively from the end thereof toward the middle, additional scutching means operating progressively on said stalks toward the ends of the stalks at one side, and other additional scutching means at the opposite side operating progressively on said stalks toward the end of the stalks at that side.
13. An apparatus for treating fibrous material, comprising in combination means for gripping stalks of fibrous material and moving them forward, two reels having longitudinally extending beater bars in interlapping relationship arranged in diagonal position with respect to the path of the stalks for operating on said stalks progressively from one end toward the middle, two other reels also having longitudinally extending beater bars in interlapping relationship arranged in diagonal position with respect to the path of the stalks at the opposite side thereof for operating on said stalks progressively from the end thereof toward the middle, a third set of reels having longitudinally extending beater bars in interlapping relationship arranged in diagonal position with respect to the path of the stalks operating progressively on said stalks toward the ends of the stalks at the side at which said first named reels are located, and a fourth set of reels having longitudinally extending beater bars in interlapping relationship arranged in diagonal position with respect to the path of the stalks at the opposite side operating progressively on said stalks toward the ends of the stalks at that side.
14. An apparatus for treating fibrous material, comprising in combination two reels having spirally arranged beater bars revolving in interlapping relationship so arranged and so timed with respect to each other that each bar of one reel at any given point along said bar moves rapidly into close proximity to the other bar and thereafter moves quickly and rapidly away, with the bearing edges of said bars at their nearest approach to each other separated sufficiently for permitting normally free movement of the stalks of fibrous material therebetween along said bars, and with the point of nearest approach of each bar of one reel to the corresponding bar of the other reel moving longitudinally of the reel, and means for feeding stalks of fibrous material into engagement with the reels and for moving the stalks longitudinally of the reels at a rate for insuring engagement of the stalks a plurality of times with the several bars successively.
15. An apparatus for treating fibrous material, comprising in combination two reels having spirally arranged beater bars revolving in interlapping relationship so arranged

and so timed with respect to each other that each bar of one reel at any given point along said bar moves rapidly into close proximity to the other bar and thereafter moves quickly 5 and rapidly away, with the bearing edges of said bars at their nearest approach to each other separated sufficiently for permitting normally free movement of the stalks of fibrous material therebetween along said bars, 10 and with the point of nearest approach of each bar of one reel to the corresponding bar of the other reel moving longitudinally of the reel, and means for feeding stalks of fibrous material into engagement with the reels and 15 for moving the stalks diagonally along the reels for a series of engagements with the several bars in succession.

16. An apparatus for treating fibrous material, comprising in combination two reels 20 having spirally arranged beater bars revolving in interlapping relationship so arranged and so timed with respect to each other that each bar of one reel at any given point along said bar moves rapidly into close proximity to 25 the other bar and thereafter moves quickly and rapidly away, with the bearing edges of said bars at their nearest approach to each other separated sufficiently for permitting normally free movement of the stalks of 30 fibrous material therebetween along said bars, and with the point of nearest approach of each bar of one reel to the corresponding bar of the other reel moving longitudinally of the reel, and means for feeding stalks of 35 fibrous material into engagement with the reels and for moving the stalks longitudinally of the reels in the same direction therealong as that in which the point of nearest approach of the bars is moving.

40 17. An apparatus for treating fibrous material, comprising in combination a table, an endless chain mounted above the table and adapted by the action of the bottom ply to move stalks of fibrous material forward along 45 the table, said table having a slot therein in alignment with said endless chain and extending under one end of said chain, a second endless chain mounted below said table having upward projections extending 50 through said slot and adapted by the action of the upper ply to move stalks of fibrous material forward along the table into position below the end of said first named chain, and other endless chain means mounted above 55 said table adapted by the action of the lower ply portion thereof to carry the stalks from the second endless chain into engagement with said first named endless chain.

60 18. The method of treating stalks of fibrous material which comprises moving the stalks along a diagonal path with respect to a pair of interlapping beater reels for feeding the stalks gradually into engagement with the reels for a progressive breaking 65 and scutching operation, and then moving

the stalks forward along a continuation of said path in engagement with a second pair of interlapping reels so arranged in diagonal position with respect to said path that the stalks are scutched progressively by 70 the action of the reels while being gradually withdrawn from the reels.

19. An apparatus for treating fibrous material, comprising in combination a table, two reels having longitudinally extending beater 75 bars revolving in interlapping relation, with the bars of each reel in angular position with respect to the adjacent portions of the bars of the other reel and with the bars of each reel moving in close proximity to the edge 80 of said table, and means for feeding stalks of fibrous material to the reels along said table in a path diagonally arranged with respect to the axes of said reels, the engagement of the stalks between oppositely disposed portions of the beater bars being intermittent only and substantially momentary at each engagement so as to permit the stalks to move freely longitudinally of the 85 reels.

90 20. An apparatus for treating fibrous material, comprising in combination a table, two reels having longitudinally extending beater bars revolving in interlapping relation, with the bars of each reel in angular position 95 with respect to the adjacent portions of the bars of the other reel and with the bars of each reel moving in close proximity to the edge of said table, and means for feeding stalks of fibrous material to the reels along 100 said table in a path diagonally arranged with respect to the axes of said reels and with the stalks arranged substantially at right angles with respect to said axes.

105 21. An apparatus for treating fibrous material, comprising in combination a substantially horizontal table, two substantially horizontal reels arranged one above the other and having longitudinally extending beater bars revolving in interlapping relation, with 110 the bars of each reel in angular position with respect to the adjacent portions of the bars of the other reel and with the bars of each reel moving in close proximity to the edge of said table, and means for feeding stalks of 115 fibrous material to the reels along said table in a path diagonally arranged with respect to the axes of said reels with a much more rapid movement longitudinally of the reels than the movement transversely of the reels, 120 the engagement of the stalks between oppositely disposed portions of the beater bars being intermittent only and substantially momentary at each engagement as the stalks move along the reels.

125 22. The method of treating fibrous material which comprises spreading a series of stalks of fibrous material along the edge of a stationary member with free end portions of the stalks projecting beyond said edge, giving

- ing said stalks a movement longitudinally of said edge and a comparatively much slower movement transversely of said member for causing the stalks to project to an increased extent as they move along the edge, supporting the stalks and the fibers momentarily against downward movement at points a short distance beyond the edge of the stationary member, and applying downward pressure on said stalks and fibers between said stationary edge and the points of momentary support for breaking said stalks.
23. The method of treating fibrous material which comprises spreading a series of stalks of fibrous material along the edge of a stationary member with free end portions of the stalks projecting beyond said edge, giving said stalks a movement longitudinally of said edge and a comparatively much slower movement transversely of said member for causing the stalks to project to an increased extent as they move along the edge, raising the stalks and the fibers momentarily by action from below progressively along said stationary edge substantially into the plane of the stationary member, and applying downward pressure progressively along said stationary edge on said stalks and fibers between said stationary edge and the points where the stalks are momentarily supported by such raising action for breaking the projecting portions of the stalks.
24. The method of treating fibrous material which comprises spreading a series of stalks of fibrous material along the edge of a stationary member with free end portions of the stalks projecting beyond said edge, giving said stalks a movement longitudinally of said edge and a comparatively much slower movement transversely of said member for causing the stalks to project to an increased extent as they move along the edge, raising the stalks and the fibers momentarily by action from below progressively along said stationary edge substantially into the plane of the stationary member, and applying pressure downwardly and lengthwise of said stationary edge progressively along said edge on said stalks and fibers between said edge and the points where the stalks are momentarily supported by said raising action for breaking the projecting portions of the stalks.
25. In an apparatus for treating fibrous material, the combination of a table, means for holding a series of stalks of fibrous material firmly in position spread along said table with their end portions projecting beyond the edge of the table and for moving the stalks forward diagonally with respect to said edge for causing the end portions of the stalks to project to an increased extent beyond the edge as the stalks move forward, a bar in spaced relation to the edge of the table in position to support the projecting portions of said stalks and fibers at substantially the level of

the edge of the table, a second bar, and means for supporting said second bar and for moving it downwardly into engagement with said stalks and fibers between said first named bar and the edge of the table for breaking the stalks.

26. In an apparatus for treating fibrous material, the combination of a table, means for holding a series of stalks of fibrous material firmly in position spread along said table with their end portions projecting beyond the edge of the table and for moving the stalks forward diagonally with respect to said edge for causing the end portions of the stalks to project to an increased extent beyond the edge as the stalks move forward, a bar, means for supporting said bar and for moving it upwardly in spaced relation to the edge of the table into position to support momentarily the projecting portions of said stalks and fibers at substantially the level of the edge of the table, a second bar, and means for supporting said second bar and for moving it downwardly into engagement with said stalks between said first named bar and the edge of the table when said first named bar is in its elevated position for breaking the stalks.

27. In an apparatus for treating fibrous material, the combination of a table, means for holding a series of stalks of fibrous material firmly in position spread along said table with their end portions projecting beyond the edge of the table and for moving the stalks forward diagonally with respect to said edge for causing the end portions of the stalks to project to an increased extent beyond the edge as the stalks move forward, a bar, means for supporting said bar in diagonal position with respect to the edge of the table and for moving it upwardly in spaced relation to the edge of the table into position to raise the projecting portions of said stalks and fibers progressively and to support such stalks and fibers momentarily at substantially the level of the edge of the table, a second bar, and means for supporting said second bar in diagonal position with respect to the edge of the table and for moving such second bar downwardly into progressive engagement with said stalks between the first named bar and the edge of the table.

28. In an apparatus for treating fibrous material, the combination of a table, means for holding a series of stalks of fibrous material firmly in position spread along said table with their end portions projecting beyond the edge of the table and for moving the stalks forward diagonally with respect to said edge for causing the end portions of the stalks to project to an increased extent beyond the edge as the stalks move forward, a reel having longitudinally arranged bars thereon revolvably mounted on an axis substantially below the edge of the table, means for rotating

- said reel for giving the bars successive movements past the edge of the table substantially in the plane of the table, a second reel having longitudinally arranged bars thereon revolu- 5
5 bly mounted on an axis substantially in the plane of the table, and means for rotating said second reel in timed relation to said first named reel for giving the bars thereon successive movements downwardly past the edge 10 of the table in close proximity to said edge of the table and also in close proximity to one of the bars of said first named reel.
29. An apparatus for treating fibrous material, comprising in combination a pair of 15 reels having longitudinally extending beater bars revolving in interlapping relationship, with the bars of one reel in position to move into close proximity to the bars of the other reel so as to engage a stalk of fibrous material 20 momentarily between them, and means for feeding stalks of fibrous material longitudinally of the reels and serving at the same time to feed the stalks gradually into engagement between said bars.
30. An apparatus for treating fibrous material, comprising in combination a pair of 25 reels having longitudinally extending beater bars revolving in interlapping relationship, with the bars of one reel in position to move into close proximity to the bars of the other reel so as to engage a stalk of fibrous material 30 momentarily between them, a stationary bar in close proximity to which the bars of said reels have their closest approach to each 35 other, and means for feeding stalks of fibrous material longitudinally of said stationary bar and serving at the same time to feed the stalks gradually into engagement between said beater bars.
31. An apparatus for treating fibrous material, comprising in combination a pair of 40 reels having longitudinally extending beater bars revolving in interlapping relationship, with the bars of one reel in position to move into close proximity to the bars of the other reel so as to engage a stalk of fibrous material 45
- momentarily between them, a stationary bar in close proximity to which the bars of said reels have their closest approach to each other, and means for feeding stalks of fibrous material longitudinally of said stationary bar and serving at the same time to feed the stalks gradually into engagement between said beater bars, the arrangement being such that the bars of one reel temporarily raise the 50 fibers by outward movement from the edge of said stationary bar and that each bar in turn of the other reel applies momentary downward pressure on the fibers between the stationary bar and the point of support by 55 the bar of said one reel.
32. In an apparatus for treating fibrous material, the combination of a table, means for holding a series of stalks of fibrous material firmly in position spread along said 60 table with their end portions projecting beyond the edge of the table and for moving the stalks forward diagonally with respect to said edge for causing the end portions of the stalks to project to an increased extent 65 beyond the edge as the stalks move forward, a reel having spirally arranged bars thereon revolvably mounted on an axis substantially below the edge of the table, means for rotating said reel for giving the bars successive 70 movements past the edge of the table substantially in the plane of the table, a second reel having spirally arranged bars thereon revolvably mounted on an axis substantially in the plane of the table, and means for rotat- 75 ing said second reel in timed relation to said first named reel serving to give the bars thereon successive movements downwardly past the edge of the table and between the edge of the table and the outer edge of one of the bars 80 of said first named reel, the arrangement of the bars on the two reels being such that such bars have their nearest point of approach shifting along the bars and along the edge of the table as rotation continues.

JOHN N. SELVIG.
